OF CHICAGO, ILLINOIS.

SPLASH-PLATE FOR CONCRETE-MIXERS.

1,056,249.

Specification of Letters Patent. Patented Mar. 18, 1913.

Application filed March 30, 1911. Serial No. 617,838.

To all whom it may concern:

Be it known that I, CHARLES E. BATHRICK, a citizen of the United States of America, and resident of Chicago, Cook county, Illinois, have invented a certain new and useful Improvement in Splash-Plates for Concrete-Mixers, of which the following is a specification.

My invention relates to concrete mixers of the kind in which a rotary receptacle is employed, and in which a movable spout is provided for the delivery of the mixture, the said spout being movable into the open side of the receptacle when the batch of concrete is ready for discharge. In the operation of a concrete mixer of this type it has been found that the said opening in the side of the rotary receptacle is productive of some trouble and annoyance, as it allows the water and wet portion of the mixture to slop over and fall outside of the mixer. This, of course, is objectionable, as it interferes to some extent with the proper mixing of the materials, involves a constant loss of cement, and keeps things outside of and around the mixer pretty well mussed up most of the time.

My invention contemplates, therefore, a concrete mixer of this general character in which the spout which moves in and out of the open side of the rotary receptacle is provided with a plate or curtain that automatically closes the opening when the spout is moved out of the receptacle to permit a batch or quantity of concrete to be thoroughly mixed before being discharged. In this way the opening in the side of the rotary receptacle is closed while the materials are being introduced and mixed, and the water and wet portions of the mixture cannot slop over, as will hereinafter more fully appear.

In the accompanying drawings, Figure 1 is a front elevation of a mixer embodying the principles of my invention. Fig. 2 is a section on line 2—2 in Fig. 1, showing the rear portion of the mixer broken away for convenience of illustration.

As thus illustrated, the mixer is of the kind commonly known as a batch mixer, being provided with a rotary cube-like receptacle A having a horizontal axis that extends through two diametrically opposite corners thereof. It has a discharge opening

a at one side thereof, and it will be understood that it has a similar opening at the other side for the introduction of the materials in the well-known and well understood manner. The said receptacle is mounted for rotation in the usual and well-known manner.

The discharge spout B is of the ordinary form, being composed of an outer stationary section b and an inner movable section b'. The outer section b is supported on a bracket arm b², and the inner section b' is supported on the sides of a swinging yoke b³, which latter is pivoted at its lower end on bearings b⁴ on the frame or base C of the machine. The section b' is above and in a position to discharge into the section b when the section b' is in the rotary receptacle, as shown in Fig. 2. In such position the section b' receives the concrete, as the latter is carried up and then dropped, and discharges it into the section b, whereby the batch is delivered from the machine. While the mixture of a fresh batch of materials is going on, the section b' is moved out to the position shown in dotted lines.

In order to prevent the water and wet portion from splashing and slopping out while the machine is in operation, and while the spout is withdrawn, a splash plate or curtain D is provided and hinged at d at its upper end to the inner end of the spout. While the machine is discharging, the said splash plate or curtain hangs inside of the receptacle, as shown in Fig. 2; but when the inner section of the spout is withdrawn, the said plate D hangs against the lower edge of the opening a, as shown in dotted lines, thus closing said opening and preventing the contents from splashing or slopping out. The action is entirely automatic, as the withdrawal of the spout is all that is necessary to cause the splash plate D to close the open side of the rotary receptacle. In this way the objectionable splashing and slopping out of the wet materials is prevented.

I do not limit myself to the exact form or construction of splash plate shown. As shown and described, it hangs in position with its upper edge presented to the falling concrete, when the machine is discharging, and consequently it does not interfere with the desired tumbling about and mixing of the concrete. But means of any suitable

character can be provided for closing the opening in the receptacle, without departing from the spirit of my invention.

What I claim as my invention is:—

- 5 1. In a mixing machine, a rotary receptacle having a discharge opening in one end thereof, a discharge spout movable into and out of the said receptacle, through the said opening, and means normally within said
- 10 10 receptacle, operable by the movement of the spout in and out of the receptacle, and held in position for closing the said opening while the machine is mixing but not discharging, said means and spout thereby alternating with each other in occupying said opening, and said means having movement relative to said spout.
- 15 2. In a mixing machine, a rotary receptacle having a discharge opening in one end thereof, a discharge spout movable into and out of the said receptacle, through the said opening, and means brought into position for closing the said opening, when the spout is moved out of the receptacle, and while the machine is mixing but not discharging, said means consisting of a plate hinged at its upper edge to the inner end of said spout, which plate is always inside of the receptacle.
- 20 3. In a mixing machine, a rotary receptacle having a discharge opening in one end thereof, a discharge spout movable into and out of the said receptacle, through the said opening, a device for operating said spout, and means thereby brought into position for closing the said opening, when the spout is moved out of the receptacle, and while the machine is mixing but not discharging, said means being carried on the said spout and movable relative thereto.
- 25 4. In a mixing machine, a rotary receptacle having a discharge opening in one end thereof, a discharge spout movable into and out of the said receptacle, through the said opening, a device for operating said spout, and means thereby brought into position for closing the said opening, when the spout is moved out of the receptacle, and while the machine is mixing but not discharging, the said means being pivoted on the said spout and movable relative thereto about a horizontal axis thereon.
- 30 5. In a mixing machine, a rotary mixing receptacle having a mixing chamber provided with a discharge opening, and a splash plate for said opening, arranged to hang a distance away from said opening and within the said chamber while the machine is discharging, and movable supporting means for said plate, whereby said plate is always vertical and movable bodily outward and held in position to close said opening when the machine is mixing but not discharging.

6. In a mixing machine, a rotary receptacle having a discharge opening in the side thereof, a discharge spout movable into and out of the said receptacle, through the said opening, and means operated by said spout for closing the said opening, while the machine is mixing but not discharging, and when the spout is moved out of the receptacle, said means consisting of a plate hinged at its upper edge to the inner end of said spout, which plate hangs inside of said receptacle, in a vertical plane at right-angles to the axis of rotation, while the machine is mixing but not discharging.

7. A mixing machine comprising a rotary receptacle provided with an axial discharge opening in one end thereof, means movable into said opening to discharge the mixture, and a splash plate inside of the mixing chamber of said receptacle, disposed in vertical position a distance back from said opening, when the machine is discharging, and in position to obstruct said opening when the machine is mixing but not discharging.

8. A mixing machine having a rotary receptacle provided with a discharge opening, a movable splash plate for said opening, a movable spout for said opening, operating means whereby said plate and spout alternate with each other in movably occupying said opening, and means whereby the angle of said plate relative to said receptacle is the same for all positions of said spout.

9. In a mixing machine, a rotary receptacle having a discharge opening in one end thereof, a discharge spout movable in and out of the said receptacle, through the said opening, and means distinct from said spout, operable by the movement of the spout out of the receptacle, and held in position for closing the said opening while the machine is mixing but not discharging, said means and spout thereby alternating with each other in occupying said opening, said means being pivotally suspended on the under side of said spout.

10. A mixing machine having a rotary receptacle provided with a discharge opening, a movable splash plate for said opening, a movable spout for said opening, the said plate and spout being distinct from each other, and operating means whereby said plate and spout alternate with each other in movably occupying said opening, said plate being pivotally suspended on the under side of said spout.

Signed by me at Chicago, Cook county, Illinois, this 27th day of March 1911.

CHARLES E. BATHRICK.
